ROTARY CUTTER

Filed May 3, 1927

Patented Oct. 16, 1928.

1,688,297

UNITED STATES PATENT OFFICE.

LOUIS E. PARENT, OF CLAREMONT, NEW HAMPSHIRE, ASSIGNOR TO CLAREMONT WASTE MANUFACTURING COMPANY, A CORPORATION OF NEW HAMPSHIRE.

ROTARY CUTTER.

Application filed May 3, 1927. Serial No. 188,458.

My invention relates to rotary cutters. It has for its object to provide an improved rotary cutter and, more particularly, an improved flock cutter. A further object of my invention is to provide improved cooling means for such a cutter whereby the temperature of the working parts, and consequently of the flock, is reduced in such a manner as to eliminate the danger from fire and to increase the productive capacity of the cutter, while reducing the labor cost per pound of product.

In the accompanying drawings, I have shown for purposes of illustration, one embodiment which my invention might assume in practice.

In these drawings:—

Fig. 1 is a central longitudinal sectional view of a flock cutter equipped with my improvements.

Fig. 2 is a smaller transverse sectional view of the inlet end of the bed shown at the right in Fig. 1.

Fig. 3 is a similar view of the outlet end of the bed, shown at the left in Fig. 1.

Fig. 4 is a reduced transverse sectional view of the cylinder, taken midway between the ends of Fig. 1 and looking toward the right.

Fig. 5 is an enlarged longitudinal sectional view of the water inlet of the cylinder.

In this illustrative construction, I have shown my invention embodied in an improved flock cutter of the construction described and claimed in my co-pending application, Serial No. 187,570, filed Apr. 29, 1927, wherein the flock to be cut is adapted to be fed through inlets 1 or 2 to a reversible knife carrying cylinder 3 which in turn cooperates with a knife carrying bed 4, the material being fed to one end or the other of the cylinder 3, depending upon the direction of operation of the latter, and discharged through suitable outlets 5, 6 at opposite ends of the bed 4; this cutter herein being provided with improved cooling means in the cylinder 3, functioning in an improved manner with the cooling means for the bed.

Considering first, the cooling means for the bed 4, it will be noted that the cooling means on the bed are the same as in my previous application mentioned. More particularly, the bed 4 is shown provided with a cooling water inlet 7 located at one end of the bed and acting to supply cooling water to the bottom of a branching upwardly extending end passage

8. This passage 8 in turn delivers at its upper ends to longitudinally extending passages 9 and 10, extending longitudinally of the upper side edges of the bed 4 on opposite sides of the knife seat or socket 11 in which the bed knives 12 are carried. Suitable transverse passages 13 extending across between the passages 9 and 10 and longitudinally spaced by the grooves in which the bed knife adjusting screws 14 are located, also serve to permit the cooling water not only to pass longitudinally from the inlet 7 but across under the knife seat or socket 11. After the water has passed through the several passages, it is also discharged through outlets 15, 16 at the top of the passages 9 and 10 and at the opposite end 55 of the bed from the inlet 7. Thus the cooling water in the bed flows from end to end and transversely of the latter from an inlet 7 at the bottom of one end of the bed to outlets 15, 16 at the top of the other end thereof. 70

In my improved construction, I have provided improved cylinder cooling means provided with inlet means adjacent the outlet end of the bed and outlet means adjacent the inlet means on the bed, and so constructed and arranged as not only to cool the cylinder and its knives, but also to cooperate with the bed cooling means, and by cooperation with the latter further reduce the temperature of the latter. More particularly, it will be noted that the cylinder 3 has suitably attached thereto for rotation therewith, as by keys 17, an axial tubular member 18. Herein, one end of this tubular member or pipe 18 also extends beyond the left hand bearing 19 of the cylinder 3 and beyond the power connection of the latter. Further, the member 18 is provided at its left hand or inlet end with an inlet or cool water supply pipe 20 extending into the same and suitably connected thereto. Herein, it enters through a gland 21 threaded into the end of the member 18 and held thereon by a gland nut 22. Further, this gland 21 compresses a coaxial packing 23 against a member 24, which in turn is pressed against an annular shoulder or flange 25 on the member 18, while the pipe 20 extends through all these members. Thus it will be noted that a watertight joint is formed which still permits the slight reciprocation of the cylinder relative to the pipe 20 which usually occurs in operation. It will further be noted that just inside the inlet end 80

100

105

of the cylinder the member 18 is provided with a lateral port 26. This port 26 in turn communicates with an enlarged cylindrical chamber 27 within the cylinder, which enables the cooling water to be brought quite close to the tool carrying outer surface of the cylinder. Further, it will be noted that a suitable abutment or stop is carried by the pipe 18, herein in the form of a plug or stopper 28 of any suitable material driven into the pipe 18, and located herein at a point slightly within the port 26 so that the water flowing through the inlet 20 is obliged to be diverted through the port 26 laterally into the chamber 27. While if desired two members 18 may be provided, it will also be noted that herein, as preferably, the member 18 is extended continuously through the chamber 27 and provided with an outlet port 29, generally similar to the port 26 but at the opposite end of the chamber 27 therefrom and herein on the same side of the cylinder axis, which enables the water in the chamber 27 to pass out of the chamber and back again into the bore of the pipe 18 on the opposite side of the plug 28. Thus the water entering through the pipe 20 into what may be called the section 30 of the bore of the member 18 is caused to pass through the port 26 into the chamber 27 and out of the latter through the port 29 into what may be called the section 31 of the bore of the member 18, while from the section 31 it passes out through a discharge pipe 32 through connections corresponding to the connections 21, 22, 23, 24 and 25, previously described in connection with the inlet. Here it will be noted that an adjustable stop 33 carried by the cutter frame cooperates with an annular groove 34 in the member 18 at a point between the bearing 19 and connection 32 to position the latter longitudinally.

In the operation of my improved construction the water entering the cylinder at the outlet end of the bed not only cools the cylinder but also tends to keep down the temperature of the bed near its outlet end, while the cool water entering the bed at the opposite end similarly acts to keep down the temperature of the cylinder adjacent its outlet, the point of minimum temperature of one thus being opposite the point of maximum temperature of the other. It will also be noted that the water entering the cylinder and leaving the same further keeps down the temperature of the cylinder bearings, thereby eliminating trouble from heated bearings. Moreover, as the water flows longitudinally beside cooling the bearing, the cool water further has some cooling effect upon the cylinder housing and the flock therein, and passing through the end walls of the cylinder also tends to keep those end walls cool. When within the cylinder it further substantially lowers the temperature of the cylinder

3, the circulation through the chamber 27 and through the inlet and outlet ports 26, 29, serving constantly to draw away any heat developed by the knives and carried inward by conduction, while the arrangement of the ports 26 and 29 serves to cause the water to be distributed over the walls of the chamber 27 while maintaining the desired circulation and keeping air from accumulating objectionably. It will further be evident that through the reduction in temperature of the body of the cylinder and of the knives carried thereon, there is a further reduction in temperature of the flock and of the bed and bed knives, as well as of the parts of the casing or supports which come in contact with either the flock, the bed, or the cylinder.

As a result of my improved construction, it is found that the temperature of the flock is kept down in such manner as entirely to eliminate the danger of fire with the loss, delay and labor incident to fires. Further, I am able to operate the cutter at substantially higher speeds than heretofore possible, and to operate it continuously at these higher speeds throughout the day without the three or four hours of idleness heretofore necessary to permit the cutter to cool after it became overheated. As a result of the higher speed and the continuous operation, both made possible by the lower temperature, it is of course also made possible substantially to increase the productive capacity of the machine during a given time limit. Thus, for example, as compared with a cutter equipped only with the improved bed of my co-pending application previously mentioned, I am able to speed up the cutter to over twice the previous possible speed. Further, due to the improved cooling I have eliminated the tendency of the solid cylinder to become so hot as to ignite the flock even when used with a water cooled bed of my previously mentioned construction. As a result, I am able to obtain over twice as much production per machine hour, and on some grades of stock over three times as much as was possible with my prior construction. At the same time the cylinder bearings are kept cool and the upkeep of the machine, as for example in connection with the knives etc., is substantially reduced. A set of knives will wear from six months to a year longer than even where only my water cooled bed is used with a solid cylinder, the excessive heating of the cylinder heretofore experienced and the consequent heating of both its knives and the knives in the bed, with the resultant softening and bending of the cutting edges of all the knives, being completely eliminated. Further, the operator is not obliged to watch for fires or be troubled with either the bearings or the knives, as is the case where a solid cylinder is used and overheating can result, and the entire mechanism consequently requiring little

or no attention, he is enabled to care for a substantially greater number of machines in a given time. In fact, as compared with the uncooled machine heretofore standard in the 5 flock cutter art, I am able to divide my labor costs per pound by ten, and when operating on some stock, by twelve or more. These and other advantages will, however, be apparent to those skilled in the art.

10 While I have in this application specifically described one embodiment which my invention may assume in practice, it will be understood that this form of the same is used for illustrative purposes and that the invention 15 may be modified and embodied in various other forms without departing from its spirit or the scope of the appended claims.

What I claim as new and desire to secure by Letters Patent is:

20 1. In a rotary cutter, a cutter carrying cylinder, a cooperating concave bed, socket means receiving said bed, and means for maintaining a circulation of cooling water through both said cylinder and said socket 25 means.

2. The combination with a flock cutter comprising a knife carrying concave bed and a cylinder carrying knives co-operating with the knives thereof, of a plurality of water 30 circulating means cooperating to withdraw excess heat generated in operation and cooling both the knives on the cylinder and those on the bed.

3. The combination with a flock cutter comprising a knife carrying concave bed and a cylinder carrying knives cooperating with the knives thereof, of a plurality of water 35 circulating means cooperating to withdraw excess heat generated in operation, one maintaining a cooling flow through the cylinder and close to the base of the knives thereon and the other a cooling flow external of the 40 cylinder and close to the base of the knives in the bed.

45 4. In a rotary cutter, a cutter carrying cylinder, a cooperating concave bed, socket means receiving said bed, and means for maintaining a circulation of cooling water through both said cylinder and socket means 50 cooperating to cool the material as it passes laterally to and from said bed.

5. In a rotary cutter, a cutter carrying cylinder, a cooperating concave bed, socket means receiving said bed, and means for 55 maintaining separate circulations of cooling water through said cylinder and socket means.

6. In a rotary cutter, a cutter carrying cylinder, a cooperating concave bed, socket 60 means receiving said bed, and means for supplying different supplies of cooling water in

opposite directions through said cylinder and socket means.

7. In combination, a concave cutter bed, a 65 concave bed socket having a cooling water inlet at its bottom and an outlet at its top and communicating water passages therebetween cooling the sides and bottom of said bed, and a cooperating cylinder having cooperating cooling means including a cooling water 70 passage therethrough.

8. In combination, a concave cutter bed, a concave bed socket having a cooling water inlet at its bottom and an outlet at its top and 75 communicating water passages therebetween cooling the sides and bottom of said bed, and a cooperating cylinder having cooperating cooling means including a cooling water 80 passage therethrough, the flow of water in said cylinder being in an opposite direction from that through said bed socket.

9. In combination, a concave cutter bed, a concave bed socket having an inlet at its bottom and an outlet at its top and communicating 85 longitudinal and transverse water passages therebetween cooling the sides and bottom of said bed, and a cooperating cylinder having an axial chamber therein and means for maintaining a circulation of the water in 90 said chamber.

10. In a rotary cutter, a concave cutter carrying bed, a concave bed socket, cooling means for the bed disposed in said socket including lateral material cooling areas along 95 each side of said bed, a knife carrying cylinder cooperating with said bed, and water cooling means for said cylinder cooling the cutters thereof and cooperating with said lateral material cooling means to cool the material between said means and said cylinder. 100

11. A water cooled tool carrying cylinder for flock cutters having an axial chamber therein and a tubular axial supply and discharge member extending through said chamber and having a stopper between its 105 ends at a point within said chamber and inlet and outlet ports on opposite sides of said stopper communicating with said chamber.

12. A water cooled tool carrying cylinder for flock cutters having an axial chamber 110 therein and a tubular axial supply and discharge member extending through said chamber and having a stopper between its ends at a point within said chamber and inlet and outlet ports on opposite sides of said stopper communicating with said chamber, said stopper being nearer said inlet port and both said inlet and outlet ports opening laterally into said chamber on the same side thereof. 115

In testimony whereof I affix my signature.

LOUIS E. PARENT.
